ADJUSTABLE LIFT HOOKS Ernest J. Day, 5440 Modoc Ave., Richmond, Calif., and
Ralph W. Berg, 2460 Fordham St., San Pablo, Calif.

Filed June 20, 1960, Ser. No. 37,159

6 Claims. (Cl. 294—81)

Our invention relates to lift means and more particularly to lift means for objects such as cylinders or the like having stub shafts extending from each end.

Among the objects of our invention are:

(1) To provide novel and improved lift means for handling objects such as cylinders or the like of different lengths;

(2) To provide novel and improved adjustable lift means adapted to handle cylinders within a wide range of lengths;

(3) To provide novel and improved adjustable lift means for cylinders or the like, which may be readily adjustable to the cylinder to be handled;

(4) To provide novel and improved adjustable lift means which substantially maintains balance throughout its range of adjustment;

(5) To provide novel and improved adjustable lift means which may be adjusted to maximum spread with inherent safety.

Additional objects of our invention will be brought out in the following description of a preferred embodiment of the same, taken in conjunction with the accompanying drawings, wherein:

FIG. 1 is a front view in elevation of the lift means of the present invention in its preferred form;

FIG. 2 is an end view of the same;

FIG. 3 is a front view similar to FIG. 1 but depicting the same in a different state of adjustment;

FIG. 4 is a fragmentary three dimensional view illustrating in enlarged detail, a feature of the present invention, and

FIG. 5 depicts a detail of the invention.

Referring to the drawings for details of our invention in its preferred form, the same comprises a coupling member, preferably in the form of a plate 1 of generally triangular shape having spaced holes 3 therethrough at its various corners, two of such holes being utilized to pivotally anchor to the plate, a pair of link members 5. The remaining hole in the coupling member is utilized for suspending the lift means from a hoist or similar apparatus.

At the free end of each link member is pivotally secured a load supporting member 7, preferably one having its load engaging end in the form of a hook 9.

Interconnecting the load supporting members are means 11 for adjustably spacing these members to accommodate the same to the load to be carried thereby. The essence of the present invention resides in the construction and assembly of the spreading means to realize a maximum range of adjustment.

The adjusting means 11, in its preferred form, includes a pair of telescoping members, the outer member 13 being hollow and open at both ends, while the inner member 14 is slideable therein and of a length corresponding to that of the outer member. The inner member is affixed at one end to one of the load supporting members 7 in spaced relationship thereto, as by a pin 15, while the outer of the telescoping members is affixed at one end to the other of the load supporting members 7 and in such manner as to leave said end open whereby the inner member may slide through and beyond said open end. A corresponding relationship is provided between the outer member and the inner member, at the secured end of the inner member, by forming a slot 16

2

in a wall of the outer member, permitting clearance around the pin 15.

To maintain the spacing between the load supporting members in any adjustment within the range of the telescoping adjusting means, the inner of the telescoping members is provided with a plurality of recesses or holes 17 therein, while on the outer of the telescoping members, we mount a spring pressed manually releasable pawl 19, operating through a hole 21 in the outer member, to engage any of the recesses or holes in the inner member which may be in alignment therewith. By manually releasing the pawl from engagement with the inner member, the spacing between the load supporting members may be quickly adjusted to the load to be carried, following which the pawl may be permitted to again engage the inner member in that recess or perforation in alignment therewith, to hold such adjustment until a change is desired.

By enabling either of the telescoping members to extend beyond the fixed end of the other, the range of permissible adjustment can be greatly enlarged, and in any event to a maximum spread which will exceed twice the minimum. When both telescoping members are capable of being so extended, a weight balance is substantially maintained, thus minimizing any probability of tilting or angular rotation of the device.

Unintentional spreading of the device beyond the maximum expansion length of the telescoping members, can be precluded by incorporating in the construction of the device, a certain definite relationship of the members. By making the overall length of the coupling plate 1 and the link members 5, 5 less than the maximum expansion length of the telescoping members, dissociation of the telescoping members cannot take place.

35 When endowed with this relationship, the device may be adjusted to maximum spread with inherent safety.

From the foregoing description of our invention in its preferred form, it will be apparent that the same fulfills all the objects attributed thereto, and while we have illustrated and described in detail, our invention in its preferred form, it will be apparent that the same is subject to some alteration and modification without departing from the underlying principles involved and we accordingly do not desire to be limited in our protection to the specific details illustrated and described except as may be necessitated by the appended claims.

I claim:

1. An adjustable lift device comprising a coupling member; a pair of load supporting members; means pivotally supporting said load supporting members from said coupling member; means for adjusting the spacing between said load supporting members, said means including a pair of members, each affixed adjacent an end thereof to one of said load supporting members and adapted to extend in a horizontal position beyond the other of said load supporting members as the load supporting members are adjusted toward each other; means slidably coupling said pair of members in horizontal position without restriction to movement of each member beyond the other end of the other member, whereby said slidably coupled members will enable said load supporting members to be adjustably spaced through a range wherein the maximum spacing will exceed twice the minimum spacing; and means for maintaining an adjusted spacing of said load supporting members within said range.

2. An adjustable lift device comprising a coupling member; a pair of link members, each pivotally attached at one end to said coupling member; a load supporting member pivotally secured to each of said link members at its free end; means for adjusting the spacing between said load supporting members, said means including a pair of members, each affixed adjacent an end thereof to one of

said load supporting members and adapted to extend in a horizontal position beyond the other of said load supporting members as the load supporting members are adjusted toward each other; means slidably coupling said pair of members in horizontal position without restriction to movement of each member beyond the other end of the other member, whereby said slidably coupled members will enable said load supporting members to be adjustably spaced through a range wherein the maximum spacing will exceed twice the minimum spacing; and means associated with said slidably coupled members for maintaining an adjusted spacing of said load supporting members within said range.

3. An adjustable lift device comprising a coupling member; a pair of link members, each pivotally attached at one end to said coupling member; a load supporting member pivotally secured to each of said link members at its free end; means for adjusting the spacing between said load supporting members, said means comprising telescoping members including an outer hollow member open at each end and an inner member, said inner member being slidable in said outer member and affixed at one end to one of said load supporting members, while said outer member, at one end is affixed to the other of said load supporting members and in such manner as to leave said end open, and means adapting said outer member to extend beyond the fixed end of said inner member, whereby said telescoping members will enable said load supporting members to be adjustably spaced through a range wherein the maximum spacing will exceed twice the minimum spacing.

4. An adjustable lift device comprising a coupling member; a pair of link members, each pivotally attached at one end to said coupling member; a load supporting member pivotally secured to each of said link members at its free end; means for adjusting the spacing between said load supporting members, said means comprising telescoping members including an outer hollow member open at each end and an inner member of comparable length, said inner member being slidable in said outer member and affixed at one end to one of said load supporting members, while said outer member, at one end is affixed to the other of said load supporting members and in such manner as to leave said end open, and means adapting said outer member to extend beyond the fixed end of said inner member, whereby said telescoping members will enable said load supporting members to be adjustably spaced through a range wherein the maximum spacing will exceed twice the minimum spacing; and latch means associated with said telescoping members for maintaining an adjusted spacing of said load supporting members within said range, said latch means including a spring pressed manually releasable pawl mounted on said outer telescopic member and adapted to engage said inner member in any of said inner member recesses, and means for precluding the permissible spreading of said load supporting means, beyond the otherwise capability of said adjusting means, said precluding means including said coupling member and link members having an overall length less than the maximum capable expansion length of said telescoping members.

5. An adjustable lift device comprising a coupling member; a pair of link members, each pivotally attached at one end to said coupling member; a load supporting member pivotally secured to each of said link members at its free end; means for adjusting the spacing between said load supporting members, said means comprising telescoping members including an outer hollow member open at each end and an inner member of comparable length and having a plurality of spaced recesses therealong, said inner member being slidable in said outer member and affixed at one end to one of said load supporting members, while said outer member, at one end is affixed to the other of said load supporting members and in such manner as to leave said end open, and means adapting said outer member to extend beyond the fixed end of said inner member, whereby said telescoping members will enable said load supporting member to be adjustably spaced through a range wherein the maximum spacing will exceed twice the minimum spacing; and latch means associated with said telescoping members for maintaining an adjusted spacing of said load supporting members within said range, said latch means including a spring pressed manually releasable pawl mounted on said outer telescopic member and adapted to engage said inner member in any of said inner member recesses, and means for precluding the permissible spreading of said load supporting means, beyond the otherwise capability of said adjusting means, said precluding means including said coupling member and link members having an overall length less than the maximum capable expansion length of said telescoping members.

6. An adjustable lift device comprising a coupling member; a pair of link members, each pivotally attached at one end to said coupling member; a load supporting member pivotally anchored to each of said link members at its free end; means for adjusting the spacing between said load supporting members, said means comprising telescoping members including an outer hollow member open at each end and an inner member, said inner member being slidable in said outer member and pin mounted at one end to one of said load supporting members, while said outer member, at one end is affixed to the other of said load supporting members and in such manner as to leave said end open, said outer member having a slot at its other end to straddle said pin mounting and extend beyond the fixed end of the said inner member, whereby said telescoping members will enable said load supporting members to be adjustably spaced through a range wherein the maximum spacing will exceed twice the minimum spacing; and means for maintaining an adjusted spacing of said load supporting members within said range.
